UNITED STATES PATENT OFFICE.

LUTHER E. EGGERTSEN, OF OAKLAND, CALIFORNIA.

DESIGN FOR A COMBINED PENRACK AND INKSTAND.

Application filed July 22, 1926. Serial No. 18,460. Term of patent 3½ years.

To all whom it may concern:

Be it known that I, LUTHER E. EGGERTSEN, a citizen of the United States, and a resident of the city of Oakland, county of Alameda, State of California, have invented a new, original, and ornamental Design for a Combined Penrack and Inkstand, of which the following is a specification, reference being had to the accompanying drawings, forming part thereof.

The figure is a perspective view of a combined penrack and inkstand, showing my new design.

I claim:

The ornamental design for a combined penrack and inkstand substantially as shown.

LUTHER E. EGGERTSEN.
